Frederick Schultz of the County of Philadelphia, Pa.,

Assignor to

Charles & Samuel Gilbert of Philadelphia, Pa.

Letters Patent No. 594. — Dated Augt 30th 1853.

The schedule referred to in these Letters Patent, and making part of the same.

To all whom it may concern:

Be it known, that I, Frederick Schultz, of the County of Philadelphia, and State of Pennsylvania have invented or produced a new and original design in Cook Stoves called the

"Evening Star,"

and I do hereby declare that the following is a full, clear, and exact description of the same, reference being had to the annexed drawings forming a part of this specification, in which—

Figure 1, is a front elevation of the stove.

Figure 2. is a rear elevation.

Figure 3. is a side elevation.

In the several figures, but one half of the symmetrical ornaments is given.— Similar letters refer to the same part of the stove or Design.

The ornamented portions of the front consist of the upper front plate A, and doors B and C. The ends of the former project over the side plates, and are embellished with the scrolls a and foliage b, arranged as seen in figure 1. In the middle of the same plate is the sunken panel D, edged with the beads c and d; and upon the panel D, is the tablet E, bearing the inscription—

"Chas. Gilbert & Co. 249, North 2nd St, Philadelphia,"

in raised capitals and numerals. In each corner of the tablet B, is a star e in bas-relief.

The door B, is raised by the moulding f, and bears the ornament F, composed of the flower g and foliage h and i, arranged and having the configuration shown in figure 1. The upper portion of the door C bears an ornament G, similar to the design E, on the door B. The lower portion of the door C, is filled with the usual draught openings.

The upper portions of the side plates H, are occupied with the doors I, which are raised above the surface of the plate by the moulding J, composed of the ovoli j, and cavetto k. The panel o is ornamented with the entwined bands and foliage m and n, scales p, and globular projections q, in bas-relief, arranged in the various details as set forth in figure 3.

Below the door I, is the inscription

"Evening Star Improved, 1853,"

in raised capitals and numerals; the inscription is surrounded by the bead l.

Beneath the inscription are the panels P and Q, and circular design R. The panel P, is raised by the moulding r, and bears the foliage s, scales t, and scrolls u, in bas-relief, arranged and having the configuration seen in figure 3. On one side, the panel P, forms a door with the same design and mouldings.

The panel Q is enclosed by the beads v and w, and bears the ornaments x, composed of foliage and flowers arranged as set forth in figure 3.

The ornament R is composed of a circle of semi-spheres, surrounded by radiating foliage resting upon clusters of fruit enclosed by a circle of stars;

26

the whole arranged as seen in figure 3. The slot W, for the reception of the spit, passes through one side of the design.

The back plate X bears the tablet Y raised by the moulding a'. Upon the tablet is the ornament b, formed of foliage, scrolls, and other devices fully set forth in figure 2, which shows the configuration of the said ornament in bas-relief. In each corner of the tablet is a star c.

The foot B' is embellished with the flowers d' and e', foliage f', scrolls h', and sweeps m', the whole arranged as set forth in figure 3.

What I claim as my production and desire to secure by Letters Patent, is-

The configuration and arrangement of the ornaments in bas-relief, and mouldings on the plates A H and X, doors B and C, oven door I, and foot B' as described in this specification and annexed drawings, forming a new and original design in Cook Stoves, known as the "Evening Star".

In testimony whereof I have hereunto signed my name before two subscribing witnesses.

(Witnesses,

Exd. Wm. Remick,
J.T.F. George Eddy. }

Frederick Shultz.
